A. D. MIZZY

ATTACHMENT FOR ARTIFICIAL TEETH UPON BRIDGEWORK

Filed June 14, 1927

Albert D. Mizzy.
Inventor

William L. Symons

Attorney

UNITED STATES PATENT OFFICE.

ALBERT D. MIZZY, OF NEW YORK, N. Y.

ATTACHMENT FOR ARTIFICIAL TEETH UPON BRIDGE WORK.

Application filed June 14, 1927. Serial No. 198,810.

My invention relates to improvements in dental devices and more especially to so-called "bridge work".

An important object of my invention is the provision of means whereby artificial teeth on so-called "bridge work" may be repaired or replaced without removing the bridge from the patient's mouth.

Another object of my invention is to provide means whereby the artificial teeth may be properly aligned regardless of the accuracy of the bridge drilling step.

Other objects and advantages of my invention will be apparent during the course of the following description.

In the accompanying drawings which form a part of this description and wherein like characters of reference denote like or corresponding parts throughout the same,

20 Figure 1 is a front view of some bridge work from which a tooth is missing,

Figure 2 is a rear elevation of the replacement tooth,

Figure 3 is an edge view of the same,

25 Figure 4 is a top plan view thereof,

Figure 5 is a vertical sectional view of the replacement tooth in place on the bridge work,

30 Figure 6 is an elevation of my improved T-bar for securing the tooth in place,

Figure 7 is a similar view showing the head member in section, and

Figure 8 is a detail view showing the application of the improved T-bar.

35 In the accompanying drawings, wherein for the purpose of illustration is shown a preferred embodiment of my invention, the numeral 10 designates the bridge work which is secured to the crown teeth 11 and supports 40 the teeth 12.

The replacement tooth 13 is provided with a longitudinal groove 14, extending part way down the tooth, and a metal backing plate 15 is riveted to the tooth and is provided with 45 a slot 16 which corresponds with the slot 14 but is narrower.

In applying the tooth an opening is drilled in the bridge work and tapped to suit the anchor shown in Figures 6 to 8 and comprising 50 a shank 17 which is provided with screw

threads adapted to engage the tapped opening in the bridge work, and a head 18 which is provided with an opening 19 to receive the reduced end 20 of the shank. A pin 21 extends through the head and shank and pivotally secures the head to the shank, the opening 19 being large enough to allow pivotal movement of the head with respect to the shank.

In operation the shank is screwed into the opening in the bridge work, until the head has assumed a vertical position in slightly spaced relation to the bridge work, and the tooth 13 is slipped over the head, the slot receiving the head, and cemented in place. 60 The reduced portion of the shank receives the portions of the backing 15 adjacent the slot 16 and allows the tooth to be slid into position. The end of the shank extending beyond the bridge work is cut off flush therewith.

In the devices of the prior art, as illustrated by the patent to Jackson, No. 921,709 of May 18, 1909, the head and shank are rigidly secured together and consequently the greatest care must be taken to drill the opening in the bridge work for the shank. The slightest deviation of this opening will affect the seating of the tooth, and will often prevent the tooth from being slipped into position.

By providing the T-bar with a pivot joint, the head may always be arranged in the proper position regardless of the direction of the opening in the bridge work, as illustrated in Figure 8.

While I have shown and described the preferred embodiment of my invention, it is to be understood that various changes in the size, shape and arrangement of parts may be resorted to without departing from the spirit of my invention or the scope of the subjoined claims.

Having thus described my invention, what I claim and desire to protect by Letters Patent is:

1. The combination with an artificial tooth having a recessed groove, of a T-shaped anchor having means for fastening to a bridge and comprising a shank, and a head pivoted intermediate its ends to the shank to move 100

about the pivot in the plane of the shank and the head and adapted to be received in the recessed groove in the tooth.

2. The combination with an artificial tooth having a longitudinal groove on its inner surface, of a T-shaped anchor comprising a shank adapted to be screwed into the bridge work, and a head having a recess intermediate

its ends and adapted to pivotally receive the end of the shank, the head and shank being arranged in the same plane at all times, whereby the head is capable of assuming its proper position regardless of the direction of the shank. 10

In testimony whereof I affix my signature.

ALBERT D. MIZZY.
